[57] CLAIM

The ornamental design for a keyboard and display unit
for a postal scale, as shown and described.

DESCRIPTION

FIG. 1 is a reduced top, front, and left side perspective
view of the keyboard and display unit for a postal scale
showing my new design;

FIG. 2 is a top plan view of the embodiment of FIG. 1
the bottom plan view is unornamented;

FIG. 3 is a front elevational view of the embodiment of
FIG. 1;

FIG. 4 is a left side elevational view of the embodiment
of FIG. 1;

FIG. 5 is a right side elevational view of the embodiment
of FIG. 1; and,

FIG. 6 is a rear elevational view of the embodiment of
FIG. 1.

FIG. 1

FIG. 2

FIG. 3

FIG. 4

FIG. 5

FIG. 6
